STOKER FIRED STEAM GENERATING UNIT WITH DOUBLE CONVECTION SECTION

Charles R. Chan, Pompton Lakes, N. J., and Charles H. Woolley, deceased, late of Cranford, N. J., by Margaret S. Chamberlin, executrix, Cranford, N. J., assignors to The Babcock & Wilcox Company, New York, N. Y., a corporation of New Jersey

Application September 14, 1954, Serial No. 455,884

2 Claims. (Cl. 122—480)

This invention relates to improvements in steam generating units. One subject of improvement is concerned with high capacity stoker fired steam generating units.

For a high capacity unit, the grate area must have a high value and the invention involves the coordination of superposed steam generating and superheating surfaces so related to the grate area that there is effective steam generation and effective control of final steam temperature over a wide load range.

Spreader stokers of high grate area are subject to concentration or laning of the combustion products arising from the stoker and such concentration or laning creates a problem as to uniformity of heat absorbing or superheating surfaces superposed with reference to the stoker. This concentration of combustion or laning of the gases is further intensified when, in a high capacity steam generating installation, oppositely arranged stokers are utilized to obtain the required grate capacity, particularly when the coal is impelled by fluid jets from positions at opposite walls of the furnace.

To overcome the above indicated concentrations of combustion products or laning of the gases arising from the stoker, the present invention involves a fuel fired vapor generating and superheating unit in which there is a particular construction of water cooled furnace having a narrowed upper portion constituting a rectangular furnace space with opposed gas outlets with the line of furnace gas exit disposed at 90° to the furnace wall along which the fuel impelling jets or other similar devices are arranged. This upper narrowed furnace chamber, or portion of the furnace, creates such flow, turbulence and mixing of the combustion products arising from the lower portions of the furnace that uniformity of combustion conditions is effected in the furnace chamber.

To attain the high total heat release for the illustrative high capacity steam generating units, the invention may involve the use of two stokers disposed alongside, with the combustion products arising therefrom passing first through a large volume radiantly heated lower furnace chamber of a cross section corresponding to the total grate area, and then to a superposed single elongated upper furnace portion in which the uniformity of combustion conditions is attained in the manner above indicated.

The illustrative vapor generating and superheating unit involves an increased path of combustion products flow from the grate to the furnace exit to promote the effective stoker firing of the unit.

Increased separation of cinders or other incombustible from the combustion gases is also promoted in the illustrative unit by the arrangement of two downflow convection gas passes at opposite sides of the unit leading downwardly from turning spaces at opposite sides of the uppermost portion of the furnace chamber. In one of these downflow gas passes, the convection fluid heating surfaces are predominantly economizer surfaces. The surfaces in the other downflow gas pass are predominantly superheater surfaces, and the control of superheat over a

2

wide load range is effected by variation and control of gas flow through the different gas passes by a regulation of dampers at the gas exits of the gas passes. For example, as the load (or rate of vapor generation) increases from a certain control point or value, the gas flow over the predominantly superheater gas pass would be decreased to compensate for the inherent characteristic of the convection superheater surfaces to effect an undesirably high steam temperature at certain load increases. Concomitantly, the gas flow through the predominantly economizer gas pass would be decreased.

The illustrative steam generating and superheating unit also involves a secondary or high temperature superheater having two sections, one located adjacent the top of the predominantly superheater gas pass, and the other located at the top of the predominantly economizer gas pass. Each of these secondary superheater sections is L-shaped with opposite tubular portions nearest the uppermost portion of the furnace chamber and with integral horizontal portions extending across the downflow of gas at the entrance to the pertinent gas pass. Each of these L-shaped secondary superheater sections preferably consists of U-tubes each with an inlet leg connected to an external inlet header, and an outlet leg connected to an external outlet header. This construction not only constitutes a drainable superheater component, but it also involves the disposition of its vertical tubular components in a zone in which this arrangement permits the separation of solids carried in suspension by the furnace gases as they pass from the uppermost part of the furnace chamber into the pertinent gas turning space.

The invention will be concisely set forth in the claims appended hereto but for a more complete understanding of the invention, its mode of operation and advantages, reference should be had to the following description which refers to the accompanying drawings, in which a preferred embodiment of the invention is described:

In the drawings:

40 Fig. 1 is mainly a vertical section through the illustrative unit, on the planes of the section line 1—1 of Fig. 2, showing the arrangement of the stoker, furnace chamber and air heater;

45 Fig. 2 is a vertical section taken on the line 2—2 of Fig. 1 and in a plane at right angles to the plane of the Fig. 1 section; and

50 Fig. 3 is a multiple plane view showing the illustrative unit partially in horizontal section and partially in plan section.

The illustrative unit is stoker fired and, to attain the necessary high heat input, two stokers, such as the stoker 10, may be employed alongside each other at such positions as indicated at 12—14 in Fig. 2. Each stoker may be of a type involving a travelling grate 16, receiving coal from a hopper 18 or it may involve a stoker having a non-travelling grate and having a series of coal impelling jets 20 arranged along the furnace wall 22 and directing streams of fuel over the stoker grate and toward the opposite wall 24 of the lower part of the furnace chamber. Such jets are associated with a hopper in which a body of coal is maintained by other apparatus, and the arrangement may be of the type indicated in the patent to Kohout 2,257,693, Sept. 30, 1941. In either case, an ash discharge device such as 26 is disposed at one end of the stoker and combustion of the fuel is promoted by the flow of high temperature air from the air heater 30 from which ductwork including the components 32—35, leads to the air inlet chamber 38 beneath the stoker grate. Combustion supporting air is thus forced upwardly through the bed of burning fuel on the stoker grate.

Above the stoker is a large volume vertically elongated

gated combustion chamber, the boundaries of which are preferably defined by rows of upright vapor generating furnace wall tubes. Some of these walls tubes, indicated at 40 and 42 in Fig. 1, line the front and rear furnace chamber walls and are connected at their lower ends to headers 44 and 46 which are supplied with water or other vaporizable liquid by means of appropriate down-comer conduits leading from the water space of the steam and water drum 48 to the lower headers. The upper ends of the vapor generating wall tubes 40 and 42 are connected to the drum 48 through the intermediary of upper front and rear wall headers 50 and 52 and appropriate circulator conduits leading from those headers to the drum. The drum is appropriately supported by hangers 240 from steel work 242 in a manner well known in the art.

Fig. 2 shows the side wall vapor generating tubes 54 and 56 leading from the lower headers 58 and 60 over the side walls of the wide lower portion of the furnace chamber generally indicated at 62. This lower portion of the furnace chamber generally corresponds in area of its horizontal section to the grate area of the subjacent stokers.

Above the lower portion 62 of the furnace chamber, the side wall tubes 56 have inwardly and upwardly inclined sections 64 combining with appropriate heat resisting material to form a wall or sloping floor for the economizer gas pass 66. Beyond the inclined sections 64 the side wall tubes leading from the header 60 have vertical sections 68 at one side of a narrowed and vertically elongated superposed furnace chamber section 70. Toward the upper part of this chamber the said wall tubes have inwardly and upwardly inclined sections 72 combined with appropriate heat resisting material to form a sloping floor or inclined wall at the bottom of the secondary superheater space 74. Beyond the section 72 the pertinent wall tubes continue as a screen having spaced upright tubular sections 76 and 78 disposed forwardly of the upright tubular sections of the vertical portion 80 of one of the secondary superheater sections. These sections form part of an L-shaped secondary superheater indicated at 80, having upright tubular sections 82 integral with horizontally extending tubular sections 84. The combined upright and vertical tubular sections constitute the U-tubes conducting steam from the inlet header 86 to the final outlet header 88.

Beyond the screen sections 76 and 78 forwardly of the secondary superheater section, the side wall tubes have roof sections 90 extending over a short distance along the roof 92 of the gas enclosing section of the unit.

At the opposite side wall of the unit, as indicated in Fig. 2, the side wall tubes 54 continue upwardly through the inclined tubular sections 100 which combine with suitable heat resisting material to form a floor or inclined wall beneath the predominantly superheater gas pass 102. Beyond this position they continue upwardly through the sections 104 at the left hand wall of the furnace chamber 70, then along the inclined wall 106 below the other L-shaped secondary superheater 108 and then as screen sections 110 and 112. From the screen sections the tubes continue upwardly through the small roof sections 114 to connection with the steam and water drum 48.

The effect of the concentration of combustion gases and other suspended solids in a zone adjacent the rear wall tubes 40, occasioned by the use of spreader stokers, is corrected by the increased gas turbulence and mixing effect of the association of the lower widened portion of the furnace chamber with the intermediate or superposed narrowed portion of the furnace 70, compelling the gases rising from the stokers to converge inwardly to the narrowed portion of the furnace chamber. This effect is further augmented by the additionally narrow uppermost portion of the furnace chamber between the

screen tubes sections 76 and 78 on one side, and the similar screen tubes sections 110 and 112, on the opposite side. From an inspection of Fig. 2 of the drawings, it will be seen that some of the wall tubes 54 pass upwardly along the outer wall 200 of the gas pass 102, and that similarly, some of the wall tubes 56 have upper extensions 202 extending along the right hand wall 204 of the gas pass 66. Beyond these extensions, these tubes have roof portions 206 extending along the roof section 92 to connection with the drum 48. Similarly, the upward extensions of the wall tubes 54 along the left hand wall 200 of the gas pass 102 have inwardly extending roof sections 210 extending along the roof section 212 to connection with the drum 48.

The arrangement and construction of the L-shaped secondary superheaters with their vertical tubular sections 80 and 120 promote the separation of cinders and other gas suspended combustion products as the gases flow beyond the screens and across those vertical sections of the secondary superheater. The arrangement of the convection elements beyond these upright sections of the secondary superheater and the provisions for downflow of gas through the gas passes 66 and 102 also further promote separation of the suspended solids which separate from the gases by reason of their downflow and by reason of their turning at 90° through the gas outlets 122 and 124 at the lower parts of the gas passes. The separated particles are collected in hopper constructions 130 and 132 from which they are periodically removed.

Control of superheat to maintain a predetermined temperature over a widely varying load range, is attained by the selective control or operation of dampers at the outlets 122 and 124 of the gas passes 66 and 102. Such dampers are indicated at 134 in Fig. 1 for the gas outlet 124. Such control or proportioning of the gas flow over the two gas passes in response to load variations may be attained by automatic control systems which are well known in the art, the gas flow being controlled by operation of the dampers in response to two or more variables, including indications of steam flow and indications of final steam temperature at or beyond the final outlet header 88 of the secondary superheater.

The outlet 124 of the gas pass 102 and the outlet construction 122 of the gas pass 66, lead to a cross duct 140 (Fig. 1) and then through ductwork or breeching 142 to the gas inlet of the air heater 30. The gases flow through the horizontally spaced upright tubes 144 of the air heater to the ductwork 146 leading to the inlet 148 of the induced draft fan 150, driven by the motor 151.

Appropriately, there are dust collecting hoppers 152 and 154 disposed respectively beneath the ductwork 142 and the air heater 30, arranged and constructed for the periodic removal of dust or solids collected from the gases. Similar dust collecting hoppers 156 are disposed beneath the cross duct 124. The air inlet of the air heater 30 is provided by a cross duct or box 220 connected by an upright duct 224 to the outlet 226 of a fan 228, driven by a motor 230. The air outlet 232 of the air heater leads from the ductwork components 32-35 to the stoker.

In the operation of the illustrative unit, feed water enters the unit at 160 and proceeds through the economizer section 162 which preferably consists of serially connected horizontally extending tubes forming a bank or tubes leading to a header at 164. From this header the partially heated feed water flows through the exterior conduit 166 to an inlet header 168 from which the feedwater flows through the banks of convection heated tubes of the successive economizer sections 170-172. From the outlet 174 of the latter, feedwater flows through appropriate connections to the drum 48. The latter has appropriate vapor and liquid separation apparatus therein acting upon the vapor and liquid mixtures

discharged into the drum by the vapor generating wall tubes.

The separated vapor passes from the upper part of the drum through appropriate tubular connections, such as 173, to a header situated at the vapor inlet 175 for the primary convection superheater sections 176 and 177. From the outlet 178 of the latter, the partially superheated steam passes by appropriate connections to the inlet headers 86 and 179 of the opposite L-shaped secondary superheaters. The outlet header 180 of the secondary superheater 108 is connected by an appropriate conduit 182 to the final outlet header 88 of the superheater.

What is claimed is:

1. In a stoker fired steam generating unit, stoker means of rectangular grate area disposed near the base of the unit, a steam and water drum symmetrically arranged in the upper end of the unit, pairs of oppositely arranged upright exterior walls extending vertically upward from said stoker means in a uniform rectangular horizontal cross-section substantially corresponding to the grate area of said stoker means, steam generating tubes defining a pair of spaced walls disposed interiorly of the enclosure formed by said upright walls and combining therewith to form a pair of downflow gas passes at opposite sides of and wholly within said enclosure, said spaced walls also defining a vertically elongated upper furnace chamber section between and opening to the upper end of said downflow gas passes, the spaced walls terminating at their lower ends in laterally extending arches within the enclosure at positions intermediate the height of the unit and substantially superjacent the stoker means, steam generating tubes extending upwardly along said upright exterior walls, said last named tubes and the tubes defining said spaced walls having their upper ends connected to said steam and water drum, steam superheater tubes arranged in one of said downflow gas passes, economizer tubes arranged in the other of said passes, and dampers arranged to control the gas flow through each of said downflow gas passes.

2. In a stoker fired steam generating unit, stoker

means of rectangular grate area disposed near the base of the unit and arranged to move a fuel bed therein, a steam and water drum in the upper end of the unit, pairs of oppositely arranged upright exterior walls extending vertically upward from said stoker means in a uniform rectangular horizontal cross-section generally corresponding to the grate area of said stoker means, steam generating tubes defining a pair of spaced walls disposed interiorly of the enclosure formed by said upright walls and combining therewith to form a pair of downflow gas passes at opposite sides of and wholly within said enclosure, said spaced walls being arranged parallel to one another and to the direction of fuel travel in said stoker means, said spaced walls also defining a vertically elongated upper furnace chamber section between and opening to the upper end of said downflow gas passes, the spaced walls terminating at their lower ends in laterally extending arches within the enclosure at positions intermediate the height of the unit and substantially superjacent the stoker means, steam generating tubes extending upwardly along said upright exterior walls, said last named tubes and the tubes defining said spaced walls having their upper ends connected to said steam and water drum, steam superheater tubes arranged in one of said downflow gas passes, economizer tubes arranged in the other of said gas passes, and dampers arranged to control the gas flow through each of said downflow gas passes.
